OPHTHALMIC FRAME WARMER

Edward A. Ebert, 203 Huxley Drive,
Snyder, N.Y. 14226

Filed June 3, 1974, Ser. No. 475,501

Term of patent 14 years

Int. Cl. D16—06

U.S. Cl. D57—1 R

Fig. 1.

Fig. 2.

Fig. 3.

Fig. 4.

Fig. 5.

FIG. 1 is a plan view of the ophthalmic frame warmer embodying my new design;

FIG. 2 is a side elevational view thereof;

FIG. 3 is an end elevational view thereof taken from the left of FIG. 1;

FIG. 4 is an end elevational view thereof taken from the right of FIG. 1; and

FIG. 5 is a bottom plan view thereof.

I claim:

The ornamental design for an ophthalmic frame warmer, substantially as shown.
